Patented Aug. 13, 1918.

FIG. 1

FIG. 3.

FIG. 4.

FIG. 5.

FIG. 2.

INVENTOR:

John L. Kozmouski,

By his attorney, Charles S. Gooding.

UNITED STATES PATENT OFFICE.

JOHN L. KOZMOUSKI, OF BOSTON, MASSACHUSETTS, ASSIGNOR TO THE RANDALL-FAICHNEY COMPANY, INC., A CORPORATION OF MASSACHUSETTS.

HYPODERMIC-SYRINGE CASE.

1,275,270.

Specification of Letters Patent. Patented Aug. 13, 1918.

Application filed October 26, 1917. Serial No. 198,721.

To all whom it may concern:

Be it known that I, JOHN L. KOZMOUSKI, a citizen of the United States, residing at Boston, in the county of Suffolk and State 5 of Massachusetts, have invented new and useful Improvements in Hypodermic-Syringe Cases, of which the following is a specification.

This invention relates to a hypodermic 10 syringe case and has for its object to provide a compact, light, convenient and hygienic case for transporting and protecting a hypodermic syringe and which also comprises compartments suitable for containing vials 15 for medicines and for syringe needles.

The invention is an improvement upon the hypodermic syringe case for which U. S. Letters Patent No. 650,348, were issued to Charles Witkowski May 22, 1900, and to 20 which reference may be had.

The object of the present invention is to overcome certain defects in the syringe case of the Witkowski patent, such, for example, as providing means to prevent the syringe 25 from being ejected from the tube by the spring which imparted a longitudinal movement to said tube containing the barrel of said syringe.

The object of the invention is further to 30 provide a stop which will not only prevent the syringe from being ejected from the slide tube by the action of the spring, but which will also act as a stop to prevent the barrel of the syringe from being rotated 35 when the same is being engaged with or disengaged from an external accessible locking device.

Again the object of the invention is to provide a cap which is so formed as to engage 40 the upper end of the holder in a manner to prevent access to the interior thereof of germs and other foreign matter.

The object of the invention is still further to provide a holder which is formed of a 45 single piece of material having a plurality of cellular compartments, said material being preferably a formaldehyde synthetic compound known as bakelite, or hard rubber.

50 The invention consists in a hypodermic syringe case formed and constructed as

hereinafter described and particularly in the combination of parts set forth in the claims.

Referring to the drawings:

Figure 1 is a front elevation of my improved hypodermic syringe case. 55

Fig. 2 is a sectional elevation taken on line 2—2 of Fig. 1.

Fig. 3 is a plan view of the same.

Fig. 4 is a sectional plan taken on line 60 4—4 of Fig. 1.

Fig. 5 is a detail sectional elevation taken on line 5—5 of Fig. 1.

Like numerals refer to like parts throughout the several views of the drawings. 65

In the drawings, 6 is the holder, preferably formed in one piece of a compound known as bakelite, or hard rubber. 7 is a cap for said holder consisting of a top 8 having a flange 9 thereon which extends 70 around the entire cap and closely fits the upper end 10 of the holder 6. The lower edge of the flange 9 abuts against a flange 11 on the holder 6. A tube 12 is fastened to the top 8 of the cap 7 and projects into a 75 centrally disposed compartment 13 provided in the holder 6.

A syringe 14 has a barrel 15 which terminates at its lower end in a screw-threaded nozzle 16. Said nozzle has screw-threaded 80 engagement with a spindle 17 which is fastened to a knob 18, said knob forming an externally accessible means by which the spindle 17 may be rotated to cause the same to become engaged with the screw-threaded 85 nozzle and thus lock the syringe barrel 15 in the compartment 13.

A spring 19 encircles the spindle 17 and bears at its lower end against the lower end 90 of the compartment 13 and at its upper end against the lower end of the tube 12, whereby said tube and the cap 7, together with the syringe contained in said tube, are moved longitudinally and outwardly from the compartment 13 of the holder 6. 95

The tube 12 has a screw 20 fast thereto and projecting into a slot which has a vertical portion 21 and an inclined portion 22, so that when the tube is moved upwardly or outwardly by the spring 19, said tube and 100 cap to which it is attached, together with the syringe, will first move upwardly in a

straight line and after the flange 9 has become disengaged from the holder 6 the screw 20 will engage the inclined portion 22 of the slot and cause the tube and cap, together with the syringe, to be turned at right angles to their former positions.

When the tube and cap are thus partly ejected from the holder 6 and are stopped by the screw 20 striking the upper end of the incline 22, the tendency is for the syringe 14 to fly out of its compartment 13 and perhaps fall on the floor, which is very undesirable, and to prevent this a stop 23 is provided comprising two arms 24 and 25, extending at right angles to the top 8 of the cap 7. The arm 25 terminates at its upper end in a lateral extension 26, there being a space 27 between the free ends of the arms 24 and 25.

20 The barrel 15 has a pair of arms 28 and 29 extending laterally therefrom. The arm 28 projects normally between the arms 24 and 25. When the tube and cap have been moved outwardly, as hereinbefore described, 25 and come to a stop, if the syringe, due to its momentum, continues said outward movement the arm 28 will engage the lateral extension 26 on the arm 25 and thus the syringe will be prevented from being ejected 30 from the tube 12. When, however, it is desired to remove the syringe from the tube 12, the same is partially rotated to allow the arm 28 to pass through the space 27 and then 35 the syringe can be withdrawn from the tube 12.

The holder 6 is provided with a plurality of compartments 30, preferably an equal number on each side of the compartment 13. The open upper ends of these compartments 40 are closed by the cap 7 and said compartments are adapted to contain vials 31 containing medicine or hypodermic needles.

The general operation of the device hereinbefore specifically and to some extent in general described is as follows: Assuming the parts to be in the position illustrated in Figs. 1 and 2, the knob 18 is rotated to disengage the spindle 17 from the screw-threaded nozzle 16 of the syringe. As soon 45 as said nozzle is disengaged from the spindle, the spring 19 acts to move the tube 12 outwardly from the holder 6. The screw 20 carried by said tube first moves upwardly in the slot 21 until the cap 7 has passed beyond the outer end of the holder 6. Said screw then engages the inclined portion 22 of the slot and rotates the tube 12, cap 7 and the syringe carried by said tube to a position 50 at right angles to that formerly occupied by said parts. The syringe is held

within the tube by the stop 23, as hereinbefore described. The user now removes the syringe, if he so desires, by rotating the same until the arm 28 passes through the space 27 and the syringe can then be withdrawn. The cap being turned at right angles to the holder, as hereinbefore described, free access may be had to any of the vials contained within the different compartments 30.

70 In returning the parts to the relative positions illustrated in Figs. 1 and 2, the reverse of the operation hereinbefore described is performed and the parts locked in position by means of the spindle 17, which is rotated to engage the screw-threaded nozzle 16 by the knob 18.

Having thus described my invention, what I claim and desire by Letters Patent to secure is:

80 1. A hypodermic syringe case having, in combination, a holder, a cap for said holder, a tube fast to said cap and slidable in a compartment in said holder, said tube adapted to receive the barrel of a syringe, a spring 85 in said compartment adapted to move said tube outwardly, an externally accessible locking device within said compartment adapted to engage and retain said barrel in said compartment against the action of said spring, and a stop on said cap adapted to engage an arm on said barrel and retain said barrel in said tube.

2. A hypodermic syringe case having, in combination, a holder, a cap for said holder, a tube fast to said cap and slidable in a compartment in said holder, said tube adapted to receive the barrel of a syringe, a spring in said compartment adapted to move said tube outwardly, an externally accessible locking device within said compartment adapted to engage and retain said barrel in said compartment against the action of said spring, and a stop on said cap comprising two arms extending at right angles to the top of said cap and between which an arm on said barrel is adapted to project, one of said arms on said cap terminating in a lateral extension projecting toward the other of said arms, there being a space between the free ends of said arms through which the arm on said barrel may pass to disengage the same from said stop.

100 In testimony whereof I have hereunto set my hand in presence of two subscribing witnesses.

JOHN L. KOZMOUSKI.
